[57] CLAIM

The ornamental design for an infant's bathtub seat, substantially as shown and described.

DESCRIPTION

FIG. 1 is a perspective view of an infant's bathtub seat, showing my new design;

FIG. 2 is a top plan view thereof;

FIG. 3 is a bottom plan view thereof;

FIG. 4 is a side elevational view thereof, the opposite side being a mirror image of the side shown;

FIG. 5 is a cross sectional view taken on line 5—5 of FIG. 2;

FIG. 6 is an exploded fragmentary cross sectional view taken on line 6—6 of FIG. 2;

FIG. 7 is a fragmentary cross sectional view taken on line 7—7 of FIG. 5;

FIG. 8 is a fragmentary cross sectional view similar to FIG. 7 showing a modified form of the infant's bathtub seat shown in FIG. 1, wherein the only difference resides in said cross sectional shape; and

FIG. 9 is a fragmentary cross sectional view similar to FIG. 7 showing a second modified form of the infant's bathtub seat shown in FIG. 1, wherein the only difference resides in said cross sectional shape.

FIG. 1.
